E. J. LACLAIR.
AUTOMATIC SAFETY DEVICE.
APPLICATION FILED OCT. 22, 1913.

Patented Nov. 10, 1914.

UNITED STATES PATENT OFFICE.

EDMUND JOHN LACLAIR, OF PROVIDENCE, RHODE ISLAND.

AUTOMATIC SAFETY DEVICE.

1,116,445.

Specification of Letters Patent.

Patented Nov. 10, 1914.

Application filed October 22, 1913. Serial No. 796,582.

To all whom it may concern:

Be it known that I, EDMUND J. LACLAIR, a subject of the King of Great Britain and Ireland, residing at Providence, county of Providence, and State of Rhode Island, have invented certain new and useful Improvements in Automatic Safety Devices, of which the following is a specification.

This invention relates to automatic brake actuating mechanism, and has for its primary object to provide means upon a locomotive or motor car whereby the brakes throughout the train system may be applied from a position upon or beside the railroad track.

A further object of my invention is to provide a device of such character as to apply the brakes throughout the train system in a quick and yet thoroughly efficient manner, with the least possible danger of any of the several parts constituting the device becoming broken or deranged in the operation, and which is so constructed and arranged as to reduce the danger of freezing 25 of the movable parts during cold weather to a minimum.

With these objects in view, together with others which will appear as the more detailed description proceeds, my invention 30 consists in the arrangement of a valve for controlling the automatic brake appliances throughout a train system, means for actuating said valve, and means adapted to be operated by a detent or other obstacle beside 35 the track for actuating said first named means.

My invention further consists in the arrangement of a valve for controlling the automatic brake appliances throughout a 40 train system, a train line controlling air cylinder provided with a piston and piston rod, said piston rod being connected in such way as to actuate the said valve, and means co-operating with a detent or other obstacle 45 beside the track for admitting air to said train line controlling cylinder.

My invention further consists in the arrangement as thus briefly set forth and means governed by the speed of the train 50 for projecting said air admitting means to be contacted by the detent or obstacle beside the track.

My invention still further consists in the arrangement of a valve in the train line for 55 controlling the brake applying apparatuses throughout the train system, a train line

controlling air cylinder provided with a piston and rod for actuating said valve, an air reservoir adapted to supply air to said valve actuating cylinder through a duct or pipe, a valve in said duct or pipe provided with the usual stem and a lever or arm secured to said stem for actuating the same, a projecting cylinder provided with a piston and rod connected to said pipe adjacent said valve for projecting the same laterally of the locomotive or car, means governed by the speed of the locomotive or car for projecting said piston, and means controllable from the locomotive cab or operator's seat 70 for resetting the detent engaging valve arm and returning the said train line valve to normal or inoperative position.

My invention still further consists in the novel arrangement and combination of 75 parts all as will be more fully described hereinafter, and particularly pointed out in the claims hereunto appended.

My invention will be more fully understood with reference to the accompanying 80 drawings, in which—

Figure 1 is a diagrammatic plan view of an automatic brake actuating mechanism constructed in accordance with my invention, Fig. 2 is an enlarged detail section 85 taken substantially upon the line x--x in Fig. 1, and Fig. 3 is a detail sectional view of a drain valve used in connection with my invention.

In carrying out my invention it is my 90 primary object to arrange a device for actuating the brakes throughout the train system automatically, and entirely independent of the controlling system operable from the locomotive cab by the engineer or operator. 95 The train line, or pipe which extends from the locomotive to the several brake appliances throughout the train, and which is indicated in the drawings generally as at 1, is as usual, controllable manually from 100 the cab by the engineer in the usual manner, and in this pipe, for the purpose of carrying out my invention, is positioned a valve 2, of any preferred construction, provided with a stem 3, squared at its outer 105 end as shown, to receive the squared opening of a valve controlling arm or lever 4.

In order that the valve, as thus briefly described, may be actuated to admit or exclude air to the train line, a train line controlling cylinder 5 is secured in any preferred manner to the frame work of the

locomotive adjacent the said valve, and said cylinder is provided with a piston 6, adapted to reciprocate therein, and equipped with a piston rod 7, extending outwardly from 5 said cylinder to be connected at its free end as at 8, to the outer extremity of the valve actuating lever or arm 4. A contractile spring 9 is interposed between the head of the cylinder 5 and the valve actuating arm 4 10 of sufficient contractile resiliency to retract the arm 4 as well as the piston 6 within the cylinder when the pressure, which is adapted to actuate the said piston, is relieved.

In order that air may be supplied to operate the mechanism above described, a reservoir 10 is provided, and this reservoir, in turn, is supplied with air by means of a pump, conventionally illustrated as at 11, and operated by a cam and rod 12 and 13 in 15 connection with the axle 14 of the locomotive. The air from the reservoir is conducted to the train line controlling system through a pipe illustrated generally at 15, and as a means of controlling the flow of 20 air therethrough, a valve 16 is provided. From this construction it will be obvious that upon the opening of the valve 16, air will be admitted to the train line controlling cylinder from the reservoir 10, and the piston 6 in the said cylinder will be forced outwardly, carrying with it the piston rod 7 and thereby actuating the valve 2 to apply the brakes in connection with the train line; upon closing the valve 16 the pressure from 25 the reservoir will be relieved in the cylinder 5 and the contractile spring 9 operates to automatically return the valve stem 3 and the piston 6 to their initial, or inoperative positions.

40 To the end that the valve 16 may be projected, by a mechanism to be more fully described later, into a position to be operated to establish communication between the train line controlling cylinder 5 and the 45 reservoir 10, by means of a detent or other obstacle adjacent the track, the air duct or pipe 15 at its medial portion is constructed of suitable metal and bent into a U-shaped form, indicated at 17, while flexible pipes 50 18, similar to those used in making pipe connections between the several cars of the train, are connected to the opposite ends of the said U-shaped section 17 and to the train line controlling cylinder and reservoir respectively. This, as will be obvious, will permit of movement inwardly and outwardly of the U-shaped section of the pipe without interfering in any way with the flow of air therethrough. The U-shaped 55 section 17 is supported upon a movable frame 19 mounted to reciprocate within a stationary frame 20 secured to the body portion of the locomotive or car. As a means of reciprocating the frame 19 laterally of the locomotive, a compression cylinder

21 is provided adjacent the rear end thereof, the said compression cylinder being provided with a reduced neck or projection cylinder 22 provided with a piston 23, to which the frame 19 is connected by means of a piston rod 24. A turn buckle is provided in the piston rod in order that adjustments of the same may be made. The contractile springs 25 are provided, each connected at one end to the compression cylinder and at the other end to the movable frame 19, in order that retrograde movement may be imparted to the said movable frame when the pressure within the compression cylinder has been relieved. A pipe or other conduit 26 is provided establishing communication between the compression cylinder 21 and the reservoir 10. The piston 23 within the projecting cylinder 22, as more clearly illustrated in Fig. 2, is provided with a port 27, adapted when moving outwardly by reason of high pressure within the cylinder 21, to register in turn with the ports 28, 29, and 30, arranged in alignment longitudinally of the projecting cylinder 22, to permit of the escape of air when the pressure is in excess of the desired amount, that is, when the more rapid reciprocations of the pump 11, due to increased speed of the locomotive, compresses such a quantity of air as to be dangerous to the mechanism if not relieved. It will be observed that when the pressure is such as to force the piston 23 to permit of registration of the port 27 with the port 30 in the projecting cylinder, the port 28 in said cylinder will be uncovered by the rear end of the said piston to permit of a double outlet.

The detent which is illustrated conventionally at 31 is positioned upon the track and in a position to operate the valve 16 when the same is in extended position and in order that the said detent 31 may operate to open the valve 16, the said valve is provided with a lever or arm 32 provided with a squared portion 33 adapted to receive the squared stem of the valve 16. The lever or arm extends outwardly from the valve 16, transversely of the railroad track when the valve is in inoperative or closed position, to be contacted by the detent 31 when the movable frame 19 is extended, as has been described. Thus it will be seen that upon rotation of the wheel shaft 14 which carries the cam 12, the pump 11 will be operated to supply the reservoir connected therewith with air, and as the pressure within the reservoir increases, the piston 23 in the projecting cylinder 22 is forced outwardly, transversely of the railroad track, and obviously projects the valve 16 into such position as to be operated by the detent 31. As the detent actuates the valve through the lever or arm 32, the air under pressure in

the reservoir 10 is admitted through the pipe line 15 to the train line controlling cylinder and, as has been previously described, the valve in the train line is operated to apply the brakes throughout the train system. As the train loses its momentum, the pressure in the reservoir obviously is reduced by reason of the ports in the projecting cylinder, and the less rapid reciprocations of the pump piston, and when the tension of the contractile springs 25 overcomes the air pressure, the frame 19 carrying with it the U-shaped section 17 of the pipe, and the valve 16, are retracted to a position to lie wholly beneath the locomotive structure.

In order that the valve 16 may be actuated to relieve the pressure in the train line controlling cylinder, a resetting cylinder 34, provided with a piston 35, and rod 36, is provided adjacent the outer end of the movable frame. A yoke 37 is secured to the piston rod 36, extending rearwardly from the cylinder to a position suitable to be engaged by a link 38, pivoted to a rearwardly extending arm 39 on the valve 16. The link 38 is secured to the said yoke by pin and slot connection as indicated at 40 in order to allow for the relative inward and outward movement of the valve 16. A pipe line 41 is extended from the reservoir 10, through the cab within convenient reach of the engineer, and down to the resetting cylinder 34, a valve 42 being shown in the portion of the pipe within the cab in order that the engineer may easily control the flow of air to the said resetting cylinder. After the operation of the brake applying device, as has been fully set forth, the engineer, through the manipulation of the valve 42, may admit air to the resetting cylinder 34, and through the operation of the piston 35 therein, the yoke 37 through the link 38 operates to exert reverse movement upon the valve stem and thereby shuts off the supply of air to the train line controlling system. A contractile spring 43 is positioned between the yoke 37 and the cylinder 34 in order that the resetting mechanism may assume normal position when pressure within the resetting cylinder 34 has been relieved.

A drain 44 is provided in the lowermost part of the reservoir. This comprises a body 45, provided at one end with means for securing the same in communication with the reservoir, an outlet 46, a valve plunger 47 in the body, and held normally in raised position by a spring 48 to close said outlet. When the pressure of air within the reservoir 10 is sufficient to overcome the pressure of the spring 48, the valve is depressed and any accumulated matter in the tank is blown out, thereby preventing freezing of the device.

I claim:

1. In an automatic brake actuating device, a detent adjacent a railroad track, a locomotive, a train line upon said locomotive and a valve in said train line, a train line controlling cylinder adjacent said valve, a piston in said cylinder, a rod connected to said piston and extending beyond said cylinder, coöperating means upon said valve and said rod for operating the former, an air reservoir, a pipe connecting said train line controlling cylinder and said reservoir and a valve provided with a stem in said pipe, means governed by the speed of the locomotive for projecting said stem into a position to be operated by said detent, and means operable from the locomotive cab for closing said valve, substantially as described.

2. In an automatic brake actuating device, a detent adjacent a railroad track, a locomotive, a train line upon said locomotive and a valve provided with a stem in said train line, a train line controlling cylinder provided with a piston and rod adjacent said valve, means connecting said piston rod and said valve stem whereby the latter will be operated upon movement of said piston, an air reservoir, a pipe connecting said train line controlling cylinder and said reservoir and a normally closed valve in said pipe, a stem in said valve adapted to be contacted by said detent to establish communication between said reservoir and said train line controlling cylinder, means governed by the speed of said locomotive for projecting said stem into a position to be operated by said detent, and means operable from the locomotive cab for closing said valve, substantially as described.

3. In an automatic brake actuating device, a detent adjacent a railroad track, a locomotive, a train line upon said locomotive and a valve provided with a stem in said train line, a train line controlling cylinder provided with a piston and rod adjacent said valve, means connecting said piston and said valve stem whereby the latter will be operated upon movement of said piston, an air reservoir, a pipe connecting said train line controlling cylinder and said reservoir, a valve in said pipe, an arm for operating said valve, a supporting frame for said pipe, a projecting cylinder, a piston in said projecting cylinder and a rod connecting said supporting frame and said piston, and means for supplying air to said projecting cylinder, substantially as described.

4. In an automatic brake actuating device, a detent adjacent a railroad track, a locomotive, a train line upon said locomotive, and a valve provided with a stem in said train line, a train line controlling cylinder provided with a piston and rod adjacent said valve, means connecting said

piston and said valve stem whereby the latter will be operated upon movement of said piston, an air reservoir, a pipe connecting said train line controlling cylinder and said 5 reservoir, a valve in said pipe, an arm for operating said valve adapted to be projected into the path of said detent, a movable supporting frame for said pipe, a projecting cylinder, a piston in said cylinder 10 and a rod connecting said piston and said movable supporting frame, means for supplying air to said projecting cylinder, and means for retracting said movable supporting frame when the air in said projecting 15 cylinder is exhausted, substantially as described.

5. In an automatic brake actuating device, a detent adjacent a railroad track, a locomotive, a train line, upon said locomotive, and a valve provided with a stem in 20 said train line, a train line controlling cylinder provided with a piston and rod adjacent said valve, means connecting said piston and said valve stem whereby the latter 25 will be operated upon movement of said piston, an air reservoir, a pipe connecting said train line controlling cylinder and said 30 reservoir, a valve in said pipe, an arm for operating said valve adapted to be projected into the path of said detent, a movable supporting frame for said pipe, a projecting cylinder, a piston in said cylinder, and a rod connecting said piston and said 35 movable supporting frame, means for supplying air to said projecting cylinder, and

means for exhausting the air in said cylinder, substantially as described.

6. In an automatic brake actuating device, a detent adjacent a railroad track, a locomotive, a train line upon said locomotive and a valve in said train line, a train line controlling cylinder adjacent said valve, a piston in said cylinder, a rod connected to said piston and extending beyond 40 said cylinder, coöperating means upon said valve and said rod for operating the former, an air reservoir, a pipe connecting said train line controlling cylinder and said reservoir, a valve provided with a stem in said pipe, means for projecting said valve and said 45 pipe outwardly to permit of said valve stem being operated by said detent, a resetting cylinder adjacent said valve, a piston in said resetting cylinder, a rod connected to said piston and projecting outwardly beyond 50 said resetting cylinder, means connecting said rod and said valve stem whereby said valve will be closed when said piston is forced outwardly, and means operable from said locomotive cab, for forcing said 55 piston outwardly, substantially as described.

In testimony whereof I have signed my name to this specification in the presence of two subscribing witnesses.

EDMUND JOHN LACLAIR.
